UNITED STATES PATENT OFFICE.

FRIEDRICH HAIZMANN, OF STUTTGART, GERMANY.

JACK.

1,132,339.

Specification of Letters Patent. Patented Mar. 16, 1915.

Application filed July 17, 1913. Serial No. 779,529.

To all whom it may concern:

Be it known that I, FRIEDRICH HAIZMANN, a citizen of the German Empire, residing at Stuttgart, in the Kingdom of Wurtemberg, Empire of Germany, have invented certain new and useful Improvements in Jacks; and I do hereby declare the following to be a full, clear, and exact description of the invention, such as will 10 enable others skilled in the art to which it appertains to make and use the same.

For lifting the axles of the front and rear wheels of motor-cars, jacks are employed which are adapted to meet the requirements 15 of axles which are at varying heights from the ground by a removable extension piece being placed on the lifting bar. In the ordinary jacks of this kind the disadvantage has been experienced that the extension 20 piece forms an independent part.

Now by the present invention this disadvantage and others resulting therefrom are avoided by the extension piece being permanently connected with the lifting appliance 25 in such a way that the connecting member also serves as a stiffener or stay for the lifting bar. In this way even when the lifting bar is drawn far out of its guides, it is stiffened and prevented from bending. 30 For this object this connecting member consists of a rod which, on the one hand, serves as a hinge-pin for the extension piece which can be turned on the rod, and also as a guide for the lifting bar. For this latter purpose 35 the rod is mounted so as to be slideable in eyes on the frame of the jack.

One form of construction of this invention will now be described as an example with reference to the accompanying drawings, in which:—

Figure 1 is a view of the jack as a whole with the extension piece turned aside; Figs. 2 and 3 are a side view and plan view respectively of Fig. 1; Fig. 4 is a plan view 45 of the extension turned aside; and Fig. 5 is a view of the jack in its highest position.

On the frame of the ordinary jack *a* an extension piece *b* is so arranged on the lifting bar *f* that it can be turned aside. For

this object it is mounted in such a way as 50 to be pivotal on a vertical rod *c* by means of which the extension piece *b* can be turned on the socket *d* when not in use. The rod *c* passes through lugs or eyes *e* in the jack frame in such a way that these eyes act to 55 guide the rod *c* when the lifting bar *f* is raised. This lifting may be done in any suitable way, for example by means of a worm *g* and worm-wheel *h* after claws *i* have been engaged beneath the axle of the 60 car. If an axle which lies lower is to be raised, the extension piece is turned aside.

In order to give the extension piece a good seat on the lifting bar *f*, it is provided with a recess *m*, which rests on suitable 65 points *n*, as illustrated in dotted lines in Fig. 1.

I claim:—

1. In a jack, the combination of a lifting part; an extension adapted to rest thereon; 70 and vertically movable means holding said extension in vertical position and constraining it when in use to move vertically.

2. In a jack, the combination of a lifting part; a vertically movable, vertically disposed rotatable rod disposed a distance from 75 the lifting part; and an extension off-set from the rod and adapted to rest upon or to be moved away from the lifting part.

3. In a jack, the combination of a frame; 80 a vertically disposed bar therein; means for raising the bar; a vertical movable rod spaced from said bar and rotatable on its vertical axis; and an extension piece mounted on the upper end of said rod, off-set 85 therefrom and adapted to be moved over and to rest upon the upper end of the bar, and to be revolved upon the vertical axis of said rod to a position entirely away from the bar.

4. In a jack, the combination of a frame; 90 a vertically movable, vertically disposed bar in said frame; means for raising said bar; a pair of perforated lugs on said frame in vertical alinement a distance from said bar; 95 a rod revoluble and vertically movable in said lugs; a vertically disposed extension piece mounted on the upper end of said

rod, off-set therefrom, and adapted to be moved over and to rest upon the top of said bar, and to be revolved upon the axis of said rod to a position entirely away from the

5 bar.

5. In a jack, the combination of a lifting part; an extension; and a rotatable and vertically slidable means holding said exten-

sion in vertical position and constraining it when in use to move vertically.

In testimony whereof I affix my signature, in presence of two witnesses.

FRIEDRICH HAIZMANN.
